UNITED STATES PATENT OFFICE.

ABRAHAM O. LEVINSON, OF CHICAGO, ILLINOIS.

HAT AND CAP.

1,207,420.

Specification of Letters Patent.

Patented Dec. 5, 1916.

Application filed February 29, 1916. Serial No. 81,115.

To all whom it may concern:

Be it known that I, ABRAHAM O. LEVINSON, a subject of the Czar of Russia, and a resident of Chicago, Cook county, Illinois, 5 have invented certain new and useful Improvements in Hats and Caps, of which the following is a specification.

My invention relates to improvements in wearing apparel and has particular reference to improvements in head coverings of 10 the variety of soft hats or caps.

The object of my invention is to reduce the number of sizes of such articles which it is necessary to manufacture and carry in 15 stock in order to be able to provide a hat or cap to fit any desired head; to eliminate the necessity of the close and accurate fitting of such articles which is desired, at the time an order is filled or a sale is made; to provide 20 such an article which shall be readily and easily adjustable through a range of several sizes and which shall be so constructed that it shall feel comfortable when in place on the head.

25 My invention consists in a hat or cap provided with an easily adjustable or self-adjusting head fitting portion or ring which is adapted to normally lie in a vertical relation to the hat or, in other words, lie flat 30 against the head.

My invention also consists in a soft hat or cap provided with a substantially continuous slot or conduit in which a band or tape of elastic material is placed and which 35 tends to contract the inner wall of the conduit to a proper head fitting dimension.

40 My invention further consists in a cap having an adjustable ear flap and provided at the junction of the ear flap with the cap with a flexible hinge joint which extends 45 around the cap and is hollow and in which an elastic tape is inserted, the ends of the tape being brought out the inner wall of the conduit through a reinforced opening so that the tension on the tape can be readily adjusted to suit.

My invention further consists in the several features of construction and in the arrangements and combinations of parts by 50 which I am enabled to attain the above and other objects and all as hereinafter described and particularly pointed out in the appended claims.

My invention will be more readily understood by reference to the accompanying 55 drawings forming a part of this specification and in which:

Figure —1— is a central vertical sectional view of a cap from front to rear and illustrating one embodiment of my invention; 60 Fig. —2— is a similar section showing the ear flap portion turned down; Fig. —3— is a bottom plan view of the cap as it appears in Fig. —1—; Fig. —4— is a vertical cross-section of a soft hat looking toward the 65 rear; Fig. —5— is a fragmentary plan elevation, showing one method of bringing the elastic tape through the wall of the conduit; and Fig. —6— is a similar view showing the manner in which I prefer to bring the ends 70 of the tape through the wall of the conduit in a soft hat.

Inventors have been busy for a long time trying to devise a practical self-adjusting hat band, and to devise means for reducing 75 the necessity of making so many different sizes of hats and caps. This necessity has become more acute in recent years due to the great development in the mail order business.

Those who buy from the mail order houses 80 do not always know the exact size they want and hence it often occurs that the articles sent do not accurately fit. This necessitates much delay and annoyance both to the customer and the house, to say nothing of the 85 great expense and actual loss in sending the articles back and forth either by mail or express. Such detrimental features of the mail order business, regarding these articles, are practically eliminated by my invention, 90 and by means of my invention but few different actual sizes of such articles need be manufactured or carried in stock.

In said drawings, A represents a cap having a soft body B and a stiff visor C. Usually 95 the body B is quite large and full in its upper portion and is brought in to head size at the lower edge thereof, which at front corresponds with the inner edge D of the visor.

I provide an inner head fitting member or flap E which may take the form of an ear covering flap which normally stands up within the cap and is adapted to be turned down to the position shown in Fig. —2—, 105 when it is desired to protect the ears. This

flap E usually extends around the sides and rear part of the cap, beginning, as shown in Fig. —3—, within the side edges of the vizor C.

5 I preferably connect the edge of the cap body with the flap E by means of a very flexible joining band F which continues clear around the head-size of the cap and is formed of an outer layer F' of cloth and a 10 similar inner layer F''. These two layers or strips are secured at one edge to the cap and at the other to the adjacent edge of the flap E, and at the front of the cap between the ends of the flap the free edges of the 15 strips F' and F'' are sewed together. I thus provide a conduit, slot or tube G which extends circumferentially around the head size of the cap in which I place an adjusting tape or band H. I preferably make a 20 single opening J in one wall of the conduit, arranging it at the rear of the hat and through this hole I draw the ends of the tape H, knotting the two ends together as best shown in Fig. —5—, to prevent them 25 being drawn back into the conduit and to preserve the head-size as adjusted. In some instances, as illustrated in Figs. —4— and —6—, I provide two of the holes or eyelets J through which I bring out the ends of the 30 adjusting tape. Such arrangement is desirable when the conduit is placed in a soft hat K in which the conduit forms a more intimate part of the lining L therein as shown in Fig. —4—. But whether I provide 35 one or two of the holes J, in each instance they serve the purpose not only of permitting the adjustment of the tape H but also of making it convenient to put in a new tape should the original tape break or 40 give out for any reason. When a single opening is used, the knot itself in the adjusting tape contacts with the eyelet and prevents the ends being drawn into the conduit and where two holes are used the fact that 45 the ends of the tape are fastened together prevents them being drawn into the conduit.

In case it is necessary to renew the tape, it can readily be threaded through the conduit through the openings which I provide.

50 It should be noted that in the case of a cap provided with a stiff vizor, the adjustment of the head-size takes place principally around the sides and back thereof and not along the front part adjacent to the vizor.

55 I usually so proportion the cap and the adjustable head-size that a single cap can be readily fitted to several sizes of heads, for instance, a seven size cap can be readily reduced to a size to fit a person requiring any 60 size down to six and one-half and similarly with other sizes. For this reason, it is not necessary to manufacture or carry in stock, under ordinary conditions, more than three sizes of any one style. This greatly reduces

the expense of manufacture and the necessary investment by the dealer, besides being of great benefit to the customer or user. Not only is the possibility of mistake in filling orders almost entirely eliminated, but after the cap has been in use should the cap 70 stretch or otherwise change its size, the user can readily adjust it to make it properly fit his head.

As many modifications of my invention will readily suggest themselves to one skilled 75 in the art, I do not limit my invention to the specific structures herein illustrated and described.

I claim as my invention:—

1. In a hat or cap, a flexible lining capable 80 of being turned down out of the hat or cap to provide additional head covering, a flexible conduit circumferentially joining the lining to the hat or cap at the head fitting part thereof, and an adjusting cord in said conduit.

2. In a cap having a flexible head-receiving part, an ear covering flap normally lying within the cap, the base of the ear flap having a circumferential conduit, and an adjusting tape extending around the cap in 90 said conduit as and for the purpose specified.

3. In a cap having a flexible head-receiving part, an ear covering flap normally lying 95 within the cap and joined at its lower edge to said head-receiving part by a circumferentially extending flexible tubular hinge-like member, an adjusting tape in said tubular member, said ear flap serving to hold 100 said tubular member in vertical relation both when within the cap and when extended.

4. In a cap having a head fitting lower edge, a substantially rigid vizor, the inner edge thereof forming one part of the head 105 fitting part of the cap, a flexible tubular band extending around and joined at one edge to the head fitting part, an ear flap joined to the free edge of the tubular member, and adapted to hold said tubular member 110 in vertical relation to the cap, and an adjusting tape in said tubular member.

5. In a cap having a head fitting lower edge, a substantially rigid vizor, the inner edge thereof forming one part of the head 115 fitting part of the cap, a flexible tubular band extending around and joined at one edge to the head fitting part, an ear flap joined to the free edge of the tubular member, and adapted to hold said tubular member 120 in vertical relation to the cap, an adjusting tape in said tubular member, and an opening in one wall of the latter through which the ends of said tape project as and for the purpose specified.

6. In a cap having a flexible head-receiving part, an ear covering flap normally lying within the cap and joined at its lower

edge to said head-receiving part by a circumferentially extending flexible tubular hinge-like member, an adjusting tape in said tubular member, the ends of said tape projecting through one wall of said tubular member, and means preventing the withdrawal of said ends into said tubular member, said ear flap serving to hold said tubu-

lar member in vertical relation both when within the cap and when extended.

In testimony whereof, I have hereunto set my hand this 25th day of February, 1916, in the presence of one subscribing witness.

ABRAHAM O. LEVINSON.

Witness:

EDWARD FAY WILSON.
